HAND PROTECTOR

Dorothy Moore Kessler, Chicago, Ill., assignor to
Mary Redfield, Chicago, Ill.

Application May 20, 1936, Serial No. 80,778

4 Claims. (Cl. 128—133)

My invention relates to the general class of baby mittens and more particularly to a device for preventing babies from sucking their thumbs or fingers.

5 One of the objects of the invention is to provide an inexpensive mitten for the above purpose which is efficient and durable, and which will not work off.

Another object of the invention is to provide 10 a mitten of the kind described which is of light weight and flexible, thus allowing the baby to move its hands and the fingers thereof with as much comfort and ease as if the hands were uncovered.

15 A further object is to provide an attractive device of the kind described which at all times may be kept clean and sanitary, and which when made in the proper sizes may be used as a surgical mitten for children or adults.

20 To this end my invention consists in the novel construction, arrangement and combination of parts herein shown and described and more particularly pointed out in the claims.

In the drawing, wherein like reference characters denote like or corresponding parts:

25 Fig. 1 is an elevational view of the mitten positioned on the infant's hand;

Fig. 2 is an elevational view of the mitten disclosing the details thereof;

30 Fig. 3 is a sectional view taken on the line 3—3 of Fig. 1; and

Fig. 4 is a sectional view taken on the line 4—4 of Fig. 2.

Referring to the drawing, the mitten comprises 35 a fabric palm section 1 and a back section 2, preferably of an oiled or otherwise treated silk or other light, water-proof or moisture resisting material, said sections being shown stitched together along the edges 3, 4, 5 and 9 to form a pocket or pouch. Obviously, the pouch could be constructed in one piece by folding the material along one of the edges and stitching, cementing or otherwise securing the other edges to form the pocket. The latter is divided into a finger-receiving portion and a thumb-receiving portion 40 7 by the parallel seams 8. The edge 9 adjacent the thumb tip is cut on the diagonal as shown in Fig. 2 or rounded, thus eliminating the sharp corner that would otherwise be formed by the edges 3 and 5 which would tend to make the thumb portion bulky and clumsy. A stiffening member 10 of celluloid or other suitable material may be inserted between the seams 8 to assist in retaining the shape and also to better prevent the baby from putting its thumb in its

mouth. In some instances additional reinforcements may be employed, or the material itself may be folded or tucked to stiffen the same.

As this part of the device is of a water-proof material, eyelets 11 are provided to allow the air to enter and ventilate the mitten. Sewed eyelets are preferred to metal eyelets.

A wrist section 12 of net or other light weight flexible material is attached to the open edges 13 of the pocket formed by the sections 1 and 2 as described, the edge 14 of the net being turned under as shown (Fig. 4) to reinforce the seam, the opposite edge of the wrist section being folded in as shown at 15 and stitched back on itself at 16 and also at 17 to form a casing for the 15 ribbon or tape 18. The ends 19 of the wrist section are turned in to avoid having ragged and unsightly edges.

In use a mitten of the proper size is slipped over the baby's hand, the fingers entering the 20 portion 6 and the thumb the portion 7 after which the net wrist section 12 is drawn together about the wrist of the baby and the ends of the tape tied to maintain the device on the baby's hand.

In this construction, a light and airy mitten is 25 formed which will effectively prevent the baby from putting its finger or thumbs in its mouth but which will not annoy or disturb the baby as would be the case with a heavier device.

The child may use the hands without being 30 handicapped, since the light, flexible, comfortable device herein shown and described does not in any way interfere with the handling of its toys, utensils or various objects. These may be grasped as freely as if the hands and fingers 35 were uncovered, thereby permitting the normal growth of the child.

Due to its fabric construction, which is preferred to rubber, the mitten can be readily washed and cleaned so that it may be maintained in a sanitary condition at all times.

The mitten also prevents the child picking on or scratching its face or ears, or picking the same, or accidentally sticking a finger in an eye, or putting the finger in the nose. Likewise it 45 may be used to advantage where there is skin disease, to prevent the spread of the same by the hands, or to enclose hand or finger bandages. Being ventilated, it is cool and comfortable. As previously mentioned, it is very satisfactory for 50 use in surgical cases, to enclose the hand and maintain dressings in place without the use of tape or tight wrappings.

Having thus described my invention, it is obvious that various immaterial modifications may 55

be made in the same without departing from the spirit of my invention; hence I do not wish to be understood as limiting myself to the exact form, construction, material, arrangement and combination of parts herein shown and described, or uses mentioned.

What I claim as new and desire to secure by Letters Patent is:

1. A mitten comprising a substantially flat hand-receiving pocket of flexible moisture resisting fabric, a wrist section of light, non-waterproof material attached thereto, and a tape running through said wrist portion adapted to secure the latter when in use.
- 15 2. A baby mitten comprising a moisture proofed fabric pocket divided into a finger-receiving portion and a smaller thumb-receiving portion, a stiffening member arranged between said finger and thumb portions, a wrist section of flexible material attached to said pocket, and a tape running through said wrist section operative to draw the latter together.
- 20 3. A mitten for preventing the sucking of

fingers, comprising a fabric palm section and a fabric back section stitched together along all of their corresponding edges but one, to form a pocket, said pocket being divided into a finger-receiving portion and a smaller thumb-receiving portion, a wrist section of lighter material having one edge thereof attached to the free edges of said pocket and having the opposite edge of said section folded back upon itself to form a casing and a tape running through said casing for drawing said wrist section together.

4. A baby mitten comprising a fabric palm section and a fabric back section stitched together along all of their corresponding edges but one, to form a pocket, said pocket being divided by parallel rows of stitching into a finger-receiving portion and a smaller thumb-receiving portion, a stiffening member arranged between said rows of stitching, a wrist section of lighter material attached to the free edges of said pocket, and a tape running through said wrist section for securing the latter to the hand.

DOROTHY MOORE KESSLER.
